(57) **CLAIM**

The ornamental design for an alignment ring for camera lens, as shown and described.

DESCRIPTION

FIG. 1 is a Bottom perspective view of an alignment ring for camera lens showing our new design;

FIG. 2 is a front elevation view thereof;

FIG. 3 is a rear elevation view thereof;

FIG. 4 is a top elevation view thereof;

FIG. 5 is a bottom elevation view thereof;

FIG. 6 is a left elevation view, the right side view being a mirror image of the left side view thereof; and,

FIG. 7 is a an enlarged elevational view of the alignment ring for camera lens taken within the lines 7—7 and 7'—7' in FIG. 2.

The broken lines shown in all views are to illustrate environment only and form no part of the claimed design.
